UNITED STATES PATENT OFFICE.

AUGUST BABINSKI, OF INDEPENDENCE, WISCONSIN.

DESIGN FOR A GRATE FOR OIL OR LAMP STOVES.

SPECIFICATION forming part of Design No. 30,857, dated May 23, 1899.

Application filed April 24, 1899. Serial No. 714,320. Term of patent 7 years.

To all whom it may concern:

Be it known that I, AUGUST BABINSKI, a citizen of the United States, residing at Independence, in the county of Trempealeau and State of Wisconsin, have invented and produced a new and original Design for a Grate for an Oil or Lamp Stove, of which the following is a specification.

This invention relates to a new and original design for a grate for an oil or lamp stove; and it has for its object to provide a design of this character that shall be both useful and ornamental.

The leading feature of the design resides in a rectangular skeleton body having interior webs and a plurality of regularly-spaced parallel transverse bars crossing above the interior webs and connecting with the longitudinal side portions of the body.

The minor features of the design are the rectangular skeleton body having a peripheral upstanding rim provided with a continuous series of scallops and also having a longitudinally-arranged elliptical center piece joined to the ends of the body by narrow necks.

Additional minor features of the design are the body being further provided with a plurality of flat vertically-disposed diagonal and transverse webs extending, respectively, from the corners and sides of the body to the elliptical center piece thereof, all of said webs being provided at their inner ends with upstanding lugs.

In the drawings, Figure 1 is a perspective view of a grate for oil or lamp stoves embodying the design contemplated by the present invention. Fig. 2 is a plan view thereof.

Referring to the accompanying drawings, the numeral 1 designates the rectangular skeleton body, provided with a peripheral upstanding flange 2, said flange having a continuous series of scallops 3. The body is further provided with a longitudinally-arranged elliptical center piece 4, which is joined to the end portions of the rim by narrow necks 5, 45 and in addition to the center piece the body is provided with a plurality of flat vertically-disposed diagonal and transverse webs 6 and 7, extending, respectively, from the corners and sides of the body to the elliptical center 50 piece 4. The inner ends of all of the flat webs 6 and 7 are arranged at the upper side of the center piece 4 and are provided with upstanding lugs 8.

The construction described provides the 55 body with a plurality of interior webs, and in addition thereto the body is also provided with a plurality of regularly-spaced parallel transverse bars 9, which cross the webs at the upper sides thereof and are connected with the 60 longitudinal side portions of the rim, as plainly shown in the drawings.

What is claimed is—

The design for a grate for an oil or lamp stove, herein shown and described. 65

In testimony that I claim the foregoing as my own I have hereto affixed my signature in the presence of two witnesses.

AUGUST BABINSKI.
